UNITED STATES PATENT OFFICE.

FRANK E. MARCY, OF SAN DIEGO, CALIFORNIA.

MILL.

Original applications filed June 7, 1927, Serial No. 197,054, and December 28, 1927, Serial No. 243,052.
 Divided and this application filed March 21, 1928. Serial No. 263,408.

This invention relates to an improvement in mills employing a rotary drum or barrel in which the material to be reduced and the necessary reducing medium such as bars, 5 pebbles, cubes, rods, etc. are confined, the material being crushed or reduced by impact and attrition as the mill load tumbles and cascades during the rotation of the mill drum.

One of the objects of my invention is to provide a mill structure in which the efficiency of the mill is materially increased, this object being accomplished in part by providing a structure for freeing the mill grate of oversize and reducing medium thereby preventing 10 plugging or blocking of the grate openings and permitting of the escape of the fines therethrough.

While in the mills of the type to which this invention is directed there is a constant migration of the mill load toward the discharge end of the mill drum due to the head provided by the continuous feeding of material to the feed end of the mill drum and the discharge 15 of this material from the discharge end, the mill of the present invention is provided with means for increasing this migrating action, the grate, however, as above mentioned being maintained free of oversize and reducing medium so as to permit of the fines which are 20 traveling forward with the migrating load to find their way readily through the grates to the outside of the mill.

In the drawings, Fig. 1 shows an embodiment of my invention in sectional elevation, the section being taken substantially on the line 1—1 of Fig. 2;

Fig. 2 is a section taken through the construction of Fig. 1 looking toward the discharge end of the mill.

Referring to the drawings in detail, 1 designates the rotary drum or barrel of the mill. This drum, as will be understood by those skilled in this art is provided with a feed head 2 and feed trunnion 3 and with a discharge head 4 and discharge trunnion 5. The trunnions 3 and 5 as is usual are mounted in suitable bearings. As this construction is conventional the same has not been illustrated.

The interior of the drum 1 is provided with stepped liners 6, these liners being so constructed and arranged as to provide liners sloping toward the discharge head 4 on the

ascending or rising side of the drum 1, thereby to effect an increase in the migrating action of the mill load toward the discharge end as 55 the drum is rotated. The mill is assumed to be rotating toward the observer as viewed in Fig. 1.

Adjacent the discharge head 4 I provide a plurality of grate sectors 7 disposed transversely of the mill drum. The grate openings 8 in the sectors extend transversely of the mill drum. Intermediate adjacent grate sectors I provide imperforate grate-retaining sectors 9, these sectors also being disposed 60 across the mill. The inner face of each of the imperforate members 9, preferably extends 65 inwardly of the mill beyond the plane of the inner face of the grate sectors.

The grate sectors 7 and grate-retaining 70 sectors 9 are assembled about a central substantially conical member 10 and are set at a slight incline so that the entire structure composed of the grate sectors 7, grate-retaining sectors 9 and conical member 10 provide a 75 substantially conical wall across the mill drum, the base of the cone facing outwardly of the mill toward the discharge end.

In the operation of this mill the migration of the mill load toward the discharge end is 80 accelerated by the provision of the sloping liners 6, as above described, sloping toward the grate and the discharge end of the mill on the ascending or rising side of the mill drum, causing the mill load to work toward 85 the feed end at an increased speed. The fines traveling with the mill load will escape through the transversely extending grate openings 8 in the grate sectors 7 and to prevent these openings from becoming plugged 90 or blocked by oversize and to prevent blocking of these grate openings by the reducing medium the imperforate grate sectors 9 have been provided, these members operating to carry the oversize and reducing medium up- 95 wardly as the drum is rotated, the oversize and reducing medium then falling upon the face of the conical shaped member 10 to be worked toward the feed end of the mill, i. e., in a direction away from the grate sectors. The 100 net result of this construction is that the grate sectors will be maintained relatively free of oversize and reducing medium at all times so as to permit of the ready escape of the fines.

through the grate openings and out of the mill.

This application is a division of my co-pending application Serial No. 197,054, filed June 7, 1927, and of my co-pending application Serial No. 243,052, filed December 28, 1927.

What I claim is:—

1. A mill comprising in combination, a rotary drum or barrel, inclined grate sectors adjacent the discharge end of the mill, solid sectors intermediate the grate sectors, a substantially conical member about which said grate sectors and solid sectors are assembled, said solid sectors and said conical member co-operating with the grate sectors to free the grate of oversize.
2. A mill comprising in combination, a rotary drum or barrel, grate sectors and solid sectors alternating disposed adjacent the discharge end of the drum, said grate sectors and solid sectors together providing a substantially conical structure extending transversely of the mill drum.
3. A mill comprising in combination, a rotary drum or barrel, grate sectors having grate openings extending transversely of the mill drum adjacent the discharge end of the mill drum, and imperforate sectors intermediate the grate sectors, said imperforate sectors cooperating with the grate sectors for freeing the latter of oversize.
4. A mill comprising in combination, a rotary drum or barrel, grate sectors disposed

across the drum adjacent the discharge end 35 thereof, and grate-retaining imperforate sectors intermediate the grate sectors.

5. A mill comprising in combination, a rotary drum or barrel, grate sectors having grate openings extending transversely of the 40 drum disposed adjacent the discharge end of the drum, and imperforate grate-retaining sectors intermediate adjacent grate sectors, the inner face of said grate-retaining sectors extending inwardly of the mill beyond the 45 plane of the grate sectors.

6. A mill comprising in combination, a rotary drum or barrel, grate sectors and imperforate grate-retaining sectors alternating disposed adjacent the discharge end of the said 50 drum, and a conical member about which the said grate sectors and grate-retaining sectors are assembled.

7. A mill comprising in combination, a rotary drum or barrel, grate sectors and imperforate grate-retaining sectors alternating disposed adjacent the discharge end of said 55 drum transversely thereof, a central conical member about which the grate sectors and the grate-retaining sectors are assembled, said 60 grate sectors, grate-retaining sectors and the central conical member being so disposed as to provide a substantially conical structure adjacent the discharge end of the mill.

This specification signed this 15 day of 65 March, 1928.

FRANK E. MARCY.
